CLAIM

The ornamental design for a combined memo paper dispenser, calendar and picture mount, substantially as shown and described.

DESCRIPTION

FIG. 1 is a perspective view of a combined memo paper dispenser, calendar and picture mount showing my new design;

FIG. 2 is a left side elevational view thereof;

FIG. 3 is a front elevational view thereof;

FIG. 4 is a rear elevational view thereof; and

FIG. 5 is a bottom plan view thereof.
